UNITED STATES PATENT OFFICE.

WALTER C. BOWERS, OF DAYTON, OHIO.

METHOD OF MAKING RING-MOUNTINGS.

1,352,870.

Specification of Letters Patent. Patented Sept. 14, 1920.

Application filed October 17, 1917. Serial No. 197,096.

To all whom it may concern:

Be it known that I, WALTER C. BOWERS, a citizen of the United States, residing in Dayton, county of Montgomery, and State of Ohio, have invented certain new and useful Improvements in Methods of Making Ring-Mountings, of which the following is a specification.

Heretofore in the production of rings having skeleton settings, it has been customary in many cases to construct the rings by hand from a unit blank of metal and also to first form the ring proper and setting separately and then braze or solder the ring and the setting together. However, such methods of manufacture were extremely expensive owing to the small output of the same and the corresponding higher wage element in the cost thereof and in the case of the soldered or brazed two-piece rings there were serious objections because of the failure of the solder in many cases to durably secure the setting to the ring.

My invention relates to the manufacture of finger-rings having skeleton settings adapted to receive precious and imitation stones and has for its objects the expeditious and economical production from a unit blank of such rings, substantially equal in appearance and durability to the best hand-carved rings, by a series of mechanical operations.

The invention is fully set forth and described in detail in the accompanying specification and drawings forming a part thereof, in which

Figure 1 is an elevation of a metal blank;

Fig. 2 is a vertical section partly in elevation of a die and punch, showing the blank as shaped therein;

Fig. 3 is a plan view of the die of Fig. 2;

Fig. 4 is a perspective of the blank, isolated, after being removed from the die shown in Fig. 2;

Fig. 5 is a vertical section, partly in elevation of a die and punch used in the flashing or spreading operation, showing the blank as shaped therein;

Fig. 6 is a plan view, from below, of the lower end of the punch shown in Fig. 5;

Fig. 7 is a plan view of the blank shown in Fig. 5, isolated;

Fig. 8 is a vertical section, partly in elevation, showing the cutter for removing the web from between the respective prongs of the ring;

Fig. 9 is a transverse section of the cutter, and

Fig. 10 is a view of a blank after the cutting operation showing the ring finished, except for the bending up of the prongs, in the dotted lines.

Referring to the drawings and the operations shown therein, the reference numeral 1 designates a shank of metal, for example, gold, which is provided with a head portion 2, the latter being preferably electrically spot-welded to said shank in the well known manner, although the same may consist of a single piece of metal, if desired. A die 3 having a recess 4 serves, when a punch 5 is forced against a blank resting on the said die, to form said blank with the configuration shown in Fig. 4, so that said blank has two outwardly flaring shank members *a* and *b*.

The blank after it is formed as shown in Fig. 4, is then introduced into the die 6 which also is recessed to conform with the configuration of the blank, as shown, and said blank is then subjected to the action of the punch member 7, which flashes the same into the form shown in Figs. 5 and 7 respectively. Said punch member 7 is provided with a conical lower end 8 which has laterally extending grooves 9 and a central projection or teat 10.

The blank as it issues from the mold 6 has a flaring or cup-shaped head consisting of radial ribs 11 with webs 12 therebetween. In order to remove the aforesaid webs, the said blank is then placed in a cutting machine in such a position, as shown in Fig. 8, that a cutter member 13 may project downwardly between the two adjacent fingers or prongs and completely cut away the intermediate web without said cutter contacting with the diametrically opposite fingers or prongs of the head such as designated by the reference numeral *c* in Fig. 8. It is necessary that the configuration of the cup-shaped head should be such that the angle of intersection of the diametrically opposite fingers thereof, when extended, should be greater than 90° and not over 116°, preferably about 112°. The angle between the face *d* of the table and the vertical face *e* as indicated by the reference letter *x*, is sufficient to accommodate a shank and finger substantially as illustrated in Fig. 8. When the ring is in the position shown in Fig. 8, the cutter member 13 can reciprocate vertically

so as to cut away the web between any two adjacent ribs without interfering in any way or coming in contact with the diametrically opposite ribs on the cup-shaped head of the ring. The ring as it issues from the cutter member as shown in Fig. 8 will have separate prongs or fingers as shown in Fig. 10 and the shanks can be readily bent into a perfect ring, as shown in the dotted lines. 10 In order to secure a stone in the said mounting, it is merely necessary to press up the prongs in the usual manner, this latter step forming no part of my invention.

It is essential that the original blank contain no joint filled with low melting point metal, such as the solder employed for joining rings and parts thereof, as under the high pressure employed in the die the head 2 would separate from the shank portion. 20 Accordingly, I preferably spot-weld a head to a shank by electricity thereby momentarily melting the shank and the head locally at their point of juncture. When cool the joint is virtually as strong as if a single piece blank having an integral head formed thereon was employed.

It is also essential that the ribs should be of such configuration that when the webs are cut away in the manner previously described, each rib will constitute a prong or claw of the desired shape, such for example as shown in Figs. 7 and 10 which represent ordinary prongs of what is known as the Tiffany setting.

35 As is evident the recess formed in the bottom center portion of the head by the projection 10, serves to extrude the metal from the bottom and force the same outwardly and upwardly. Thereby the metal is forced 40 into the grooves 9 and the formation of the ribs is facilitated and the employment of an excessively large head or knob is avoided. This is especially desirable, since the metal in the center of the bottom of the cup-shaped 45 head is later removed by punching or drilling so as to admit the light to the bottom of the stone and facilitate cleaning.

As shown in Fig. 8 the shanks extend at substantial right angles to each other so 50 that the same snugly embrace the sides *f* and *g* of the table or support therefor of the cutting machine.

Having thus described my invention, what I claim and desire to secure by Letters Patent is:—

1. The method of making a finger ring which consists in first forming a blank having a rectilinear shank and a solid central

head integrally joined therewith without the intervention of a metal of low melting point, 60 bending said blank so as to form two shanks extending substantially at right angles to each other from said head, flashing said head so as to form a cup-shaped member having superficial ribs on its upper surface, 65 each rib projecting in such direction that it would, if extended, intersect the extension of a portion of the cup diametrically opposite thereto at an angle greater than a right angle, then rigidly supporting said blank 70 and removing the intermediate metal webs between the aforesaid ribs.

2. The method of making a ring which consists in first forming a blank having a rectilinear shank and a solid central head 75 integrally joined therewith without the intervention of a metal of low melting point, bending said blank so as to form two shanks extending substantially at right angles to each other from said head, flashing said head so as to form a cup-shaped member having superficial ribs on its upper surface, 80 each rib projecting in such direction that it would, if extended, intersect the extension of a portion of the cup diametrically 85 opposite thereto at an angle greater than a right angle, then rigidly supporting said blank and causing a reciprocating metal cutter to successively contact with the metal in close proximity to two adjacent ribs without contacting with a diametrically opposite metal portion of the cup so as to cut 90 away the metal webs between the ribs.

3. The method of making a blank for a finger ring consisting in first forming a 95 blank having a rectilinear shank and a central head joined together, bending said shank to form two shanks extending at an angle to each other from the head, flashing said head to form a cup-shaped member, then rigidly supporting said blank and removing portions thereof in spaced relation providing intermediate fingers.

4. The method of making a blank for a finger ring consisting in first forming a 105 blank having a head having two shanks extending at an angle to each other from the head, flashing said head to form a cup-shaped member, then removing portions of said head in spaced relation providing intermediate fingers.

In witness whereof, I have hereunto set my hand at the city of New York, county and State of New York, this 16th day of October, 1917.

WALTER C. BOWERS.
